ATTORNEY-S

UNITED STATES PATENT OFFICE.

SAMUEL W. HYATT, OF CONNERSVILLE, INDIANA, ASSIGNOR TO INDIANA LAMP CORPORATION, OF CONNERSVILLE, INDIANA, A CORPORATION.

ELECTRIC PLUG.

Application filed February 7, 1927. Serial No. 166,423.

This invention relates to a connector plug particularly adaptable for mounting light bulbs.

The chief object of the invention is to simplify the present type of connector plugs and eliminate several of the parts heretofore employed by arranging the parts of the solid path connector plug such that they serve for the same purpose as other parts heretofore have served.

The full nature of the invention will be understood from the accompanying drawings and the following description and claims:

In the drawings Fig. 1 is a central sectional view through the metal shell and associated parts, the insulation body being shown in elevation. Fig. 2 is a section taken on line 2—2 of Fig. 1 in the direction of the arrows. Fig. 3 is an elevational view of the insulation body with a portion shown in half section to show other parts in detail. Fig. 4 is a transverse section taken on line 4—4 of Fig. 1 and in the direction of the arrows.

In the drawings there is illustrated an insulation body 10 having formed integral therewith or suitably secured thereto a peripherally enveloping collar or flange 11. Herein said body and flange collar are cylindrical but need not necessarily be so formed. Extending longitudinally through the body are a pair of bores 12 and rigidly mounted in each is a terminal member 13 having an enlarged exposed contact head 14 and a longitudinally recessed opposite end 15. The plug body is suitably recessed as at 16 and the terminal member 13 is provided with a transverse threaded opening 17 in alignment with the opening 16. When the contact terminal is seated in its bore 12 a screw 18 is adapted to rigidly clamp the end of the wire 19 in the aperture 15 of the terminal. The end 19 is a part of the lead-in wire having suitable insulation 20. The resultant construction, therefore, is that each of the terminals are rigidly anchored to the plug body 10 and each of the wire ends 19 is also rigidly anchored thereto and is in electrical connection with the supporting terminal 13, whereby there is obtained a rigid solid path connector for the wire 19 to the contact, button or enlargement 14.

A metal shell 21 is shown provided with

a flared enlargement 22 and a cylindrical extension 23 thereof is threaded and associated therewith is a threaded extension 24 of a rear shell or retainer having a reduced shoulder portion 25 and a tubular extension 26 continuing therefrom. A coil spring 27 has one end engageable upon the contracted portion 25 of the rear shell and bears upon the collar 11 for normally maintaining the plug body in the projected position, reference being had to the open end of the forward shell. Outward movement of the plug body is limited by the collar 11 engaging the annular shoulder 22 of the forward shell.

To prevent relative rotative movement between the plug body and the shell to insure accurate predetermined positioning of the terminal contacts 14, the plug body is provided with one or more longitudinally extending grooves 28 and the shell supports a pin 29, and said pin is seatable in said groove, thereby permitting longitudinal relative movement between the shell and the plug body, but preventing rotative movement. Pin 29 is shown extending outwardly from the shell as at 30 and positioned oppositely therefrom is another pin 31. Pins 30 and 31 thus are diametrically positioned with respect to each other upon the metal shell 21 and are adapted to be received by a bayonet slot, at one end of a connector or sleeve mounting which is also provided with a bayonet slot at the opposite end to receive the bayonet pins on a light bulb, said sleeve and said light bulb being of standard constructions heretofore employed.

The invention claimed is:

1. A plug connector including a cylindrical insulation body, a cylindrical shell slidably supporting the same, yielding means normally tending to project the body from the shell, cooperating means on the shell and body limiting such movement, a contact having an exposed end and movable with and carried by the body, and a pin and slot connection preventing relative rotative movement between the body and shell, the pin of said connection projecting laterally of the shell for bayonet connection and shell anchorage.

2. A device as defined by claim 1, characterized by the opposite end of the contact terminating short of the opposite end of the

body, a lead in wire connected to the opposite end of the contact, and a single member simultaneously maintaining rigid connection therebetween and securely anchoring both contact and lead in wire to said body.

3. A device as defined by claim 1, characterized by the shell projecting beyond the

body at one end and terminating short thereof at the opposite end whereby the insulation body normally is fully projected.

10

In witness whereof, I have hereunto affixed my signature.

SAMUEL W. HYATT.
